M. C. STILES & T. C. LEWIS.
MACHINE FOR MAKING WINDOW BLINDS.

No 10,462.

Patented Jan. 24, 1854.

UNITED STATES PATENT OFFICE.

MOSES C. STILES AND TRISTRAM S. LEWIS, OF HOLLIS, MAINE.

MACHINE FOR MAKING WINDOW-BLINDS.

Specification of Letters Patent No. 10,462, dated January 24, 1854.

To all whom it may concern:

Be it known that we, MOSES C. STILES and TRISTRAM S. LEWIS, of Hollis, in the county of York and State of Maine, have invented 5 a new and useful Machine for Making Window-Blinds; and we hereby declare the following to be a full and exact description thereof, reference being had to the drawings herewith presented, which drawings 10 constitute a part of said description.

This machine consists of the following essential parts, viz., first the frame and cutter by which the stile is grooved or mortised; and secondly the gouge by which the 15 slats are cut to their exact length and rounded or formed so as to exactly fit the mortise by one movement of the foot on a treadle. See the drawing.

Figure 1 is an isometrical view of the 20 whole table and frame (T, T, T, T). (F F,) is the sliding frame which supports the arbor (A) on which is fixed the cutter (C) and its pulley (P). It also has another arbor (B) with pulleys (D and E) to drive 25 the cutter. This frame is fitted in grooves in the two posts (G and G,) so as to slide freely up and down. It is lifted and supported by the spring (S,) seen lying across the bottom girder of the frame. This frame 30 is depressed by the treadle or lever (L) which is connected to the slide-frame by the rod (R²). The lever projects a little beyond the frame on both sides so that the operator may stand on either side. In order to give 35 the mortise the proper bevel we use a fence or rule placed diagonally on the table at a proper distance from the cutter in order that when a stile is pressed against the rule (K) the cutter stands over the center of the 40 stile; this rule should be spaced off in inches and quarters or into proper distances for the mortises and should be a little longer than the stile.

Now to use this machine we first put the 45 cutter in motion by the belt. Then lay the stile against the rule. Bring the end of the stile exactly even with the first mark next to the cutter. Then press down the treadle and a mortise is instantly made in its proper 50 position. Then raise the foot so that the cutter will rise clear of the stile, move the stile along even with the second mark on the rule, and depress the treadle again. Repeat the operation until the stile is mortised

to its proper length. Thus it will be perceived that all the mortises may be made complete in this way in less time than they could be marked out in the common way and with perfect accuracy, for to set out a diagonal mortise requires four marks; but 60 to cut the mortise in this machine only requires one movement of the hand and one of the foot on the treadle. It may be observed that there is a small block or stopper (I) placed behind the cutter and secured to the 65 cutter frame, the lower end of which strikes down upon the top of the stile and stops the cutter from descending lower than to give the mortise a proper depth.

The cutter is constructed in a particular 70 manner. It may be seen in Fig. 3 and Fig. 4. The two teeth (Y, and Y,) are knife-edged at the points to cut down the sides of the mortise and the tooth (Z) is made with chisel point to cut out the wood between 75 them. The former should be a little longer than the latter.

In Fig. 1 will be seen a projection or 80 bench (W) over which hangs the gouge (J) carried by a short arm (H) which is secured to the frame (F) and strikes down upon the bench (W). In using the gouge we fix a gage block or stop on the bench in such position as to stop the slat at the right 85 distance from the gouge so as to cut the slat to the exact length required at one stroke. Thus the slat is brought to its length and rounded without measuring, then turning it end for end and at the next motion of the 90 treadle and gouge around the other end and 95 it is finished; thus by two motions of the foot a slat is cut to its length and rounded at both ends, completely fitting the mortises.

We do not claim the cutter, chisel, or any 95 part of the machine separately, but

What we do claim and desire to secure by Letters Patent is—

The combination of the cutter C and chisel J worked simultaneously by the foot of the 100 operator, or by other power, in the manner and for the purposes set forth.

MOSES C. STILES.
TRISTRAM S. LEWIS.
